DETACHABLE FOOTWEAR PAD

Carl Mayer and Edith Mayer, Hampstead,
London, EnglandApplication September 7, 1940, Serial No. 355,844
In Great Britain December 7, 1939

1 Claim. (CL 36—36)

This invention relates to improvements in or modifications of footwear with detachable heel and sole pads or parts thereof and has for its object to provide improved means whereby a sole or heel pad may easily be attached to or detached from a boot or shoe, while at the same time the pad will be applied firmly to the boot or shoe when mounted in position without any possibility of detachment or displacement.

According to this invention, the means for mounting a detachable heel or sole pad on footwear consists of a series of interlocking elements the complementary parts of which are disposed on the footwear and on the detachable part respectively in spaced relationship around the edges and a locking element for locking the detachable pad against disconnection from the footwear.

In an embodiment the interlocking means disposed around the edges of the footwear consist of a series of hooks or headed studs formed in spaced relationship out of a strip or plate of metal, the hooks or studs following the outline of the sole or heel and the plate being attached to the footwear as by nails or screws, the detachable sole or heel pad, for example of rubber, having formed or moulded therein corresponding recesses in which said hooks or headed studs can engage simultaneously when the detachable pad is placed in position by sliding substantially in the longitudinal direction of the footwear.

In another embodiment the strip or plate of metal is dispensed with and the hook or headed studs or other suitable elements of similar nature are secured individually in spaced relationship along the edge of the footwear sole or heel, the detachable sole or heel pad having corresponding recesses as before.

The said recesses will, of course, be shaped in accordance with the nature of the elements with which they are to be interlocked and for example in the case of hooks being employed on the footwear the recesses would have the shape of small cavities sufficiently deep to take the hooks and said cavities would be partly covered by a wall or diaphragm formed out of the material of the detachable sole or heel pad, so as to constitute a pocket for the reception of the hook with the said wall or diaphragm engaging over the underside of the head of the hooks. The recesses may be lined or covered with a metal element, which may be let or moulded into the material of the detachable pad, for example, the aforesaid

wall or diaphragm may be substituted by a suitably shaped and apertured metal washer.

In the case where the hooks or other elements are formed out of a strip of metal as aforesaid 5 the said strip, if applied to a sole, may be suitably curved to follow the curved plane of the sole for comfort in walking.

The locking element may consist of a screw 10 passing through the detachable pad and engaging in a female thread formed for example in a metal bush let into the sole or heel of the footwear. Any other suitable locking means may be employed, as will be described later.

In some cases the arrangement of the interlocking elements may be reversed, the hooks or 15 the like being disposed on the detachable pad and the recesses or pockets on the footwear.

Various embodiments of the invention will 20 now be described by way of example with reference to the accompanying drawing, wherein:

Figure 1 is a longitudinal sectional view of a shoe heel which has fixed thereto a rubber heel pad with the aid of connecting means constructed according to the invention;

Figure 2 is an inverted plan view of the shoe heel with one of the interlocking elements fixed thereto;

Figure 3 is a sectional view similar to Figure 1 of another embodiment;

Figure 4 is a view similar to Figure 2 of the second embodiment;

Figure 5 is a plan view of a rubber heel pad adapted to be pressed upon and secured to the shoe heel illustrated in Figure 4;

Figure 6 is an inverted plan view of a shoe heel showing alternative interlocking elements; and

Figure 7 is a perspective view of an interlocking element as used in the embodiment shown in 40 Figure 6.

Referring to Figures 1 and 2, the shoe heel 1 has secured thereto as by nails 2 a metal plate 3 formed with five hooks 4 which are adapted to engage in corresponding pockets 5 of the rubber heel pad 6. It will be seen that each pocket is in the form of a recess partly covered with a wall or diaphragm 7 moulded integrally with the rubber heel pad, the said hooks 4 being adapted to engage under the walls or diaphragm 7 when

50 the hooks are positioned in the recesses 5 and the rubber heel pad is slid longitudinally with reference to the shoe heel (towards the left in Figure 1). To prevent accidental detachment of the rubber heel pad from the shoe heel a screw 55 8 is passed through registering holes in the rub-

ber heel pad 6, the plate 3 and the shoe heel 1 and the said screw may be tightened or loosened for removal by means of any suitable instrument or conveniently by means of a coin which the wearer would normally carry in his pocket. For firmness the aperture in the rubber heel pad 6 for taking the screw 8 may be lined with a washer 9. The plate 3 may be secured to the shoe heel 1 by means of five nails 2 shown near the periphery of the plate 3 in Figure 2, and additional nail holes 10 may be provided in the plate 3 if greater security of attachment is required.

Referring to the embodiment shown in Figures 3 to 5 the shoe heel 1 has again secured thereto a metal plate 11 which has only three hooks 12 as distinct from the five hooks 4 shown in Figures 1 and 2. The pockets 5 for receiving the hooks 12 are similar to those shown in Figures 1 and 2 but in this embodiment means are provided to dispense with a screw for preventing accidental detachment of the rubber heel pad 13 from the shoe heel 1. Such means consist of a tongue 14 pressed out of the material of the plate 11, the latter being made of suitable material for this purpose, for example tempered steel plate, to provide a springy tongue. The rubber heel pad 13 has moulded therein in addition to the hook receiving pockets 5 a recess 15 in the face applied to the underside of the shoe heel as shown in Figure 5, and on the wearing face the rubber heel 13 has moulded therein a slot 16 which communicates with the recess 15. When, for mounting the rubber heel pad 13, same is placed against the underside of the shoe heel 1 so that the hooks 12 engage in the recess 15, the springy tongue 14 is temporarily bent back towards the shoe heel and as the rubber heel pad is slid longitudinally with reference to the shoe heel 1 with a view to engaging the hooks 12 under the webs 7 of the pockets, the springy tongue 14 will eventually spring back into the recess 15 and will prevent movement of the rubber heel pad 13 in the direction in which the hooks 12 can be disengaged from under the webs 7. To enable the rubber heel pad 13 to be removed by movement in this direction when so desired a suitable instrument such as a screw driver or coin is inserted into the slot 16 to press back the tongue 14 out of the recess 15 and the tongue is held in such pressed

back position until the hooks 12 are disengaged from under the webs 7, whereupon the rubber heel pad will fall off.

The embodiment shown in Figure 6 separate hooks 17 are provided, each being mounted in the correct position for example by two nails 18. The hook 17 is shown in perspective view in Figure 7. The rubber heel pad shown in Figure 5 is readily applicable to this embodiment as the springy tongue 14 could advantageously be made in one piece with the central hook 17 but the screw connection described with reference to the embodiment shown in Figures 1 and 2 may also be employed.

15 We claim:

Means for mounting detachable resilient heel and sole pads on footwear having a non-recessed attaching face, comprising a plate of less dimensions than the contour of the portion of the shoe 20 to which it is attached, said plate having a pair of rearwardly extending offset hooks at one end and a single rearwardly extending hook at the other end and disposed in a longitudinal plane extending between said pair of hooks, and also 25 having an integral spring locking tongue struck out from the body, said tongue presenting a relatively wide free locking edge of the same vertical depth as the thickness of the metal plate from which it is formed, a pad having undercut 30 pockets for receiving said hooks and also having a recess for receiving said tongue, one wall of said recess forming an abutment for the wide free locking edge of the said tongue, and said pad having a slot at the location of the tongue 35 recess to render said tongue accessible to a tool inserted therein from the outer face of the pad to enable the said free edge of the tongue to be moved out of locking engagement with the wall of the recess and into the space in the plate caused by its formation so that the tongue in fully unlocked position will lie flush between the opposite faces of the plate and permit ready disengagement of the hooks from the undercut recesses, said pad having the inner marginal portion of the pad flushly engaging the portion of the said attaching face to conceal the edges of the plate.

CARL MAYER,
EDITH MAYER.
